Primary Examiner — Mark A Goodwin(74) *Attorney, Agent, or Firm* — INNOVATION CAPITAL LAW GROUP, LLP; Vic Lin(57) **CLAIM**

The ornamental design for a coal shearing drum as shown and described.

DESCRIPTION

FIG. 1 is a perspective view of a coal shearing drum, showing our new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof; and,

FIG. 7 is a front elevation view thereof.

The broken lines in the drawings illustrate portions of the coal shearing drum that form no part of the claimed design.

1 Claim, 7 Drawing Sheets(56)
